UNITED STATES PATENT OFFICE.

ALBERT L. GALUSHA, OF SHARON, MASSACHUSETTS.

TAR EXTRACTOR AND SCRUBBER.

Application filed May 3, 1920. Serial No. 378,393.

To all whom it may concern:

Be it known that I, ALBERT L. GALUSHA, a citizen of the United States of America, residing at Sharon, in the county of Norfolk and State of Massachusetts, have invented certain new and useful Improvements in Tar Extractors and Scrubbers, of which the following is a full, clear, and exact description.

10 In the manufacture and use of gas for illuminating, industrial, or power purposes, and particularly in the production of producer gas, it is desirable, if not essential, that the solid, liquid and gaseous impurities which come over with the gas from the generator, such as tar, be entirely removed, and the gas cleansed and purified before use. Many forms of tar extractors and gas cleaners have been devised and used for 20 this purpose, but no apparatus has been heretofore produced of this character that fully meets the practical requirements of efficiency, reliability and economy of operation.

25 The primary object of my present invention has been to produce such an apparatus which will more nearly meet these requirements, and this I have accomplished by the apparatus which I shall hereinafter set forth and describe and which, in general terms, comprises means for removing the tar and other impurities from the gas characterized by the following improvements and functions.

30 The tar and impurities are removed more perfectly and completely than heretofore by other devices, and this action is assured at all times without the necessity of constant care and attention being bestowed by the user of the device. The power required to drive the apparatus is very materially reduced, the result largely of means which involve a greatly improved method of applying the water, the consumption of which is greatly reduced. The gas leaves the apparatus at a constant pressure, the amount of which is readily and easily fixed by the operator. The apparatus as a whole is materially reduced in size, as well as cost of 40 construction and so designed that it may be readily inserted into any gas line and operated with ease and economy and without the necessity of putting the gas under pressure. This latter advantage follows largely from the fact that the device comprises, among other improvements, a single rotat-

ing part which acts both as a purifier and as a blower.

The construction and operation of the apparatus by which the above new results are secured will be described in detail by reference to the accompanying drawings, in which—

Fig. 1 is a view in side elevation of the complete purifier attached to a gas producer.

Fig. 2 is an enlarged view in elevation and part section of the purifier proper.

Figs. 3 and 4 are sectional views on planes at right angles designed to illustrate details of the apparatus as well as the theory of its operation.

Fig. 5 is a sectional detail on the line 5—5 of Fig. 2.

The gas producer, familiarity with which is assumed, is designated in Fig. 1 by numeral 1. From this device a vertical pipe 2 leads and is connected with a parallel pipe 3 and a horizontal pipe 4, connected with the purifier. These pipes are provided with the usual and necessary valves, connections and other appurtenances common in this art, and are of such length that the tar and similar impurities contained in the hot gas are cooled sufficiently, by radiation in the vertical portions, to condense the tarry constituents therein from vapors to liquid form before reaching the purifier.

The impure gas entering through the pipe 4, passes into a chamber 5 Fig. 2 and thence into a chamber 6 at the end of a cylindrical casing 7, containing the means for extracting the impurities. Through this casing 7 extends a shaft 8 connected with an electric or other motor 9 by means of which a rapid rotation may be and is imparted to it.

The interior of the casing 7, free from all projections and protuberances, is divided into a plurality of chambers 6 and 10 by diaphragms 11 with central openings therein through which passes the shaft 8. In each chamber 10 there is mounted on the shaft 8 a fan or rotor 12, Figs. 2, 3 and 4, open on the side of the opening at the left 105 in the partitioning diaphragm and closed on the other side by a disk 13 of a diameter closely approximating that of the interior of the casing 7.

The gas entering the chamber 6 passes 110 through the central opening in the diaphragm 11 into the central part of the rotat-

ing fan. By this it is set in rapid rotation, and as a result of centrifugal force all the particles therein which are of greater specific gravity than the gas proper are thrown 5 radially outward toward the walls of the casing in which the fan revolves.

Above the casing 7 is a pipe 14 from 10 which extend branch pipes 15 opening into the casing and adapted to deliver a relatively limited flow of water upon the wall of said casing, but not into the rotors. The whirling body of air or gas within the casing causes this water to adhere to and flow over the interior walls of the casing, as 15 indicated in Fig. 4, where 17 designates the sheet or film of water over the lower portion of the casing walls.

From each chamber 10 leads a drain pipe 16 which extends down below the surface 20 of a body of water in a tank 18, Fig. 2 forming a water seal. The water introduced into the casing 7 by the jets 15 flows out of the same by way of the drain pipes 16 and all solid or liquid particles, thrown 25 by centrifugal force onto and into this film or sheet of water are entrained thereby and carried off by such flow into the tank 18. Such particles are largely the drops more or less minute of tar, and may be periodically 30 or constantly drawn off from the tank, the lighter floating parts by an upper overflow pipe 19, the heavier by a discharge pipe 20 at the bottom of the tank.

Considering for a moment the operation 35 of the first fan 12, which is the same as all the others, the gas entering this fan contains more or less solid impurities including globules of tar. The larger of these globules are immediately thrown outward into 40 the film of water, but some of the globules are so minute that they are not so readily thrown by centrifugal action and not taken up by the flowing water film. To bring about a coalescence of these more minute 45 particles the clearance between the fan and the inner wall of the casing is made quite small, and when the particles, following the flow of the gas, are brought into this narrow clearance space, the moving particles 50 are brought into collision or rubbing contact with the relatively stationary particles, and by this action and perhaps by their electrification they are caused to coalesce and form larger droplets or globules which 55 are more readily projected into and taken up by the filming water. This theoretical action is illustrated in Figs. 3 and 4.

The correctness of this assumption seems to be borne out by the unquestionable fact, 60 that the reduction of the clearance space results in a much more perfect elimination of the tar. It is true that one operation may not result in the complete removal of the tar, and that some particles may pass on with 65 the gas around the outer edge of the first

disk 13 into the second chamber 10. For this reason I use a plurality of fans and diaphragms, so that the slightly impure gas after the first or second cleansing may pass to a second or third or more fans and there undergo a series of similar cleansings. The power to drive two or more fans in a single apparatus of this nature is but slightly greater than that required for one, and I therefore use two or more fans in order to 75 more perfectly cleanse and purify the gas. The last fan of the series is, in practice, not used to throw the solid particles into a water film, the water jet 15 of this chamber not being usually open, but this fan operates 80 chiefly to dry the gas before it leaves the purifier.

The above description of construction and operation covers the more prominent and essential features of my improved apparatus. The following considerations, however, will more clearly and fully illustrate the nature of the invention and certain details which are important, if not essential, to its successful operation. 85

If water be sprayed into the gas and upon the fans, not only is a greater amount of water required, but the power necessary to drive the fans is enormously increased. Moreover, by passing the gas over the surface of the water as I do, the impurities are extracted as completely and effectively as by spraying the water into the gas. By my plan the expense of operation is very greatly reduced and a more perfect action 100 secured. Moreover, it is extremely difficult, if not impossible, to remove all of the fine particles of tar solely by centrifugal force, but by applying this force in a machine in which those particles of tar are brought 105 into collision and caused to coalesce into larger particles which are subject to centrifugal action, as I have above set forth, very perfect purification of the gas may be effected. The apparatus furthermore permits the soluble impurities in the gas to 110 dissolve in the water and be thus eliminated, without the necessity of spraying the water into the body of gas.

The apparatus as constructed also permits of a much more perfect cooling and cleaning of the gas. By the elongated passage into the purifier the gas is cooled to the desired extent. The gas is cooled by radiation without the user's having to buy water 115 for this cooling purpose. If it became necessary to warm the tar in order to keep it in a fluid state, this may be done without warming the gas itself, but only the outlets from the apparatus. For example, the tank 120 18 may be jacketed and warmed by any convenient gas or fluid, or a stream of warm water as waste water from a gas engine jacket can be run into the tank and there mixed with waste gas wash water, etc. 125 130

It will be noted that each fan in addition to cleansing the gas, produces a negative atmospheric pressure at the central opening of the diaphragm and a positive pressure at 5 the periphery of the disks 13, so that each rotating part serves not only as a scrubber and tar extractor, but also as a means for putting the gas under pressure.

The purified gas issues from the apparatus through the pipe 21. At this outlet the pressure is regulated at the will of the operator by varying such pressure by means of a by-pass 22 containing a valve 23. This valve closes an orifice having a bevelled edge 10 so that when the valve is fully closed, the contacting surfaces are of extremely small dimensions, a mere line, in fact, so that there is no tendency of the valve to stick. The pressure of the valve may be adjusted 15 in any known manner, as by weights or springs for example. The valve is shown as carried by a pivoted arm 24, secured to a bar 25, carrying adjustable weights 26 which may be set to secure any constant pressure. 20 25 A very slight increase in gas pressure in 22 will cause the valve to open a trifle and the flow of gas to the suction side of the apparatus will cause the pressure to drop to the correct amount, with the result that the 30 opening of the valve is reduced and the correct pressure maintained. In practice, the valve is open to a slight degree at all times so that there is no contact between it and its seat to cause sticking.

5 It will be observed that there is more pressure at the right of the disks 13 than on the other side thereof, which will result in some end thrust on the shaft. This should be provided for by the use of a thrust bearing 31 for the shaft. The other bearings that carry 40 the entire rotating parts may be ordinary floating bearings, and the end of the shaft is covered by an air tight cap 27, which avoids the use of a stuffing box and prevents 45 the escape of gas at the pressure end of the device. At the other or suction end there is no tendency to leak outward and no stuffing box is needed.

If extraction of tar and impurities is desired but less increase in pressure, the rotors 50 by any suitable means may be adjusted with reference to the diaphragms at their left. For example the rotors may be secured to the shaft 8 by screw bolts 30 passing through 55 their hubs or by inserting or withdrawing washers 32 between the thrust bearing 31 and the journal box 33, the shaft at the right hand end having a certain amount of play or lost motion, as shown. This increases the clearance between the fans and 60 the diaphragms to their left and decreases the volume of gas output of the fan and the outlet pressure.

The intake 4 and the outlet 21, it will be 65 observed, are in line, which renders it a sim-

ple and easy matter to insert the apparatus into any existing gas line. These parts are further provided with connections 28 for attachment to vertical pipes in case it be required to join up the device to such pipes. 70

This apparatus possesses to a very marked degree all of the advantages above set forth. It has few and simple parts. All internal parts are not in contact, but separated by large clearances, so that the apparatus is 75 little liable to sticking, clogging or other derangement and in its operation it has been found most economical and efficient.

What I claim is:—

1. In a gas purifier, the combination with 80 the chambers of a cylindrical casing having smooth interior wall surfaces, of centrifugal fans or rotors within the chambers adapted to receive the gas at the center and force it around and radially onto the peripheral 85 wall surfaces of the chambers, water pipes passing through the peripheral wall of said chambers and constituting the only projections on or in contact with said walls, and adapted to deliver and direct water onto the 90 walls of the casing chambers only, where it is retained by the centrifugally driven gas out of contact with the rotors, and outlets or drain pipes from the bottom of the casing chambers to carry off the water and 95 its entrained impurities.

2. In a gas purifier, the combination with 100 the chambers of a cylindrical casing having a smooth interior wall surface, of water pipes passing through the peripheral walls 105 of said chambers and constituting the only projections on or in contact with said walls, centrifugal fans or rotors within the casing chambers adapted to receive gas at the center and throw the same around and radially 110 toward the said peripheral wall surfaces with a force which is sufficient to maintain the water delivered from the pipes thereon and out of contact with said rotors and drain pipes for carrying off the water with 115 its entrained impurities.

3. In a gas purifier, the combination with 120 a cylindrical casing and diaphragms having central openings dividing said casing into a plurality of chambers with smooth 125 interior walls, water pipes passing through said walls and constituting the only projections on or in contact therewith and adapted to deliver water onto the said walls only, a centrifugal fan in each chamber closed on one side and adapted to throw gas upon 130 said walls with sufficient force to maintain the water thereon, outlets at the bottom of each chamber, and means for introducing gas to be purified to the central part of a fan at one end of the casing and discharging it through a corresponding opening at the other end of said casing.

4. In a gas purifier, the combination with 135 a cylindrical casing and diaphragms with

- central openings dividing said casing into a plurality of chambers with smooth interior peripheral walls, of a rotary fan in each chamber, the spaces between the blades of each fan being closed by a disk or plate, water pipes passing through the peripheral walls of the chambers and constituting the only projections on or in contact with said walls and which deliver water upon said walls only, drain pipes from the bottom of each chamber immediately under the fans and in the direct line of the projected particles of tar, means for rotating the fans and means for introducing gas into the central part of the first fan of the series, said fans being all of the same construction and serving to purify the gas and force it through the casing from the center of one fan to the peripheral wall of the casing and back to the center of the next fan in the series.
5. In a gas purifier, the combination with a casing divided into communicating chambers, a rotary fan in each chamber, means for delivering water directly and only upon the wall of said chambers where it is retained by the gas thrown by the fans and out of contact with said fans, a drain pipe from the bottom of each chamber, and a tank

adapted to be heated for maintaining the tar therein in liquid form.

6. In a gas purifier, the combination with a casing of a series of rotary fans mounted on a horizontal axis and by means of which a gas with its impurities subjected to centrifugal action is thrown against the walls of the casing, of means for delivering directly onto the interior walls of the casing films of water which are retained on said walls and out of contact with the fans by the action thereon of the gas in its travel over the same, and which films take up and remove the impurities from the gas.

7. In a gas purifier, the combination with a casing divided into chambers communicating at their centers, of rotary fans in said chambers adapted to throw the particles of tar in a gas outwardly by centrifugal force towards the casing wall, and to serve as blowers for forcing the gas through said series of fans, of a regulable by-pass through which a determined part of the gas may be carried repeatedly through the series of fans.

In testimony whereof I hereto affix my signature.

ALBERT L. GALUSHA.
